UNITED STATES PATENT OFFICE.

JAMES E. SELSOR, OF PHILADELPHIA, PENNSYLVANIA, ASSIGNOR TO THE
GERMANTOWN TOOL WORKS, OF SAME PLACE.

DESIGN FOR A HAMMER.

SPECIFICATION forming part of Design No. 16,729, dated June 8, 1886.

Application filed October 17, 1885. Serial No. 190,214. Term of patent 14 years.

To all whom it may concern:

Be it known that I, JAMES E. SELSOR, a citizen of the United States, residing in the city and county of Philadelphia, State of Pennsylvania, have invented and produced a new and original Design for a Hammer, of which the following is a specification, reference being had to the accompanying drawing, forming part thereof.

The leading feature of my design for a hammer is the head thereof having a concaved neck and many-sided poll, the outer end of the latter having a circular outline, and the inner ends of the sides of the said poll being curved, substantially as shown.

A represents the head of a hammer, and B

the neck and C the poll thereof, said neck joining the eye portion of said poll. The neck is curved in cross-section and concave or swelling in opposite directions from the center 20 to the ends, and the poll is many-sided and has its outer end of circular form.

I claim--

A design for a hammer having a head with a concave neck and a many-sided poll, the 25 outer end of the latter being of circular form and the inner ends of the sides thereof being curved, substantially as shown.

JAMES E. SELSOR.
